U.S. Appl. No. 16/392,552, filed Apr. 23, 2019, Michael McCall.

(Continued)

Primary Examiner — Austin Murphy(74) *Attorney, Agent, or Firm* — Shane Cortesi(57) **CLAIM**

The ornamental design for a brush drying device, substantially as shown and described.

DESCRIPTION

FIG. 1 is a front perspective view of a brush drying device showing my new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

Broken lines in each of the figures indicate brushes.

Broken lines in FIGS. 2, 3, 5-7 indicate an on/off switch.

Broken lines in FIG. 7 indicate vents on the bottom of the brush drying device and components inside the brush drying device.

All broken lines indicate unclaimed subject matter.

1 Claim, 7 Drawing Sheets(56)
